LOUIS FOURNIER AND GÉRARD MANG, OF PARIS, FRANCE.

COMPUTING MACHINE.

Application filed January 25, 1922. Serial No. 531,805.

To all whom it may concern:

Be it known that we, LOUIS FOURNIER and GÉRARD MANG, citizens of the Republic of France, both residing at Paris, France, have ⁶⁰ invented new and useful Improvements in Computing Machines, of which the following is a specification.

The present invention relates to improvements in the tens-carrying mechanism of computing machines of the type in which a movable tooth is caused to project from the stepped drum at the desired moment with a view to actuating the number-wheel of the immediately higher numerical order. A ⁶⁵ mechanism of this type is described in applicants' French Patent 522856 of August 25, 1920 and in applicants' U. S. application Serial No. 321045, filed September 2, 1919.

The improvements forming the subject of ⁷⁰ the present invention are intended, in a general manner, to give the machine greater speed in operation, to reduce the resistance to movement of the parts and to securely lock said movable tooth so as to prevent it ⁷⁵ from accidental displacement.

In the accompanying drawings, a form of execution of these improvements has been shown by way of example.

Figure 1 is a transverse section of the machine ⁸⁰ showing the arrangement employed for carrying tens, that is to say, for placing the movable tooth of the stepped drums in the desired position for causing the disc of the immediately higher numerical order to ⁸⁵ advance by one tenth of a revolution.

Figure 2 is a partial horizontal section showing details of this mechanism.

In a calculating machine, it is indispensable that the operation of the different parts ⁹⁰ shall be extremely rapid, in view of the fact that these parts actuate each other and that this succession of actuating movements would be liable, if not provided with means permitting of effecting this very rapidly, of slowing down the action of the machine to such an extent that the services rendered thereby would be diminished.

This is the case especially as regards what may be called the accessory actions of a calculating machine, which form a branch of the general operation of the machine. This is the case with the mechanism known as the "tens-carrying device" the purpose of which is to arrange certain parts in the required position when a disc has recorded

nine units of any order, so that, at the moment when it is going to record a tenth and consequently indicate zero, the disc of immediately higher order is advanced by one ⁶⁰ unit.

In the device described in French Patent 522856, this carrying of tens is effected by a movable tooth 72 which comes into engagement with the movable calculating wheel 76 mounted upon the axis of the next ⁶⁵ following wheel, this movable tooth not appearing and, consequently, not being capable of coming into action, except at the exact moment when the disc of a lower order accomplishes the tenth and last portion of its ⁷⁰ rotation. The manner in which the appearance of the tooth 72 was brought about in the original device did not allow either of obtaining sufficiently rapid movements as not to slow down the general operation considerably, or of absolute fixity of the movable tooth when in its operative position.

The improvements made in this device consist, on the one hand, of a mechanism actuated more directly by the disc and ⁸⁰ designed to exert a pull on the flange 68' of the part 68 so as to move the rod 68⁴ longitudinally to push the movable tooth 72 outwards, this mechanism being provided with an accelerator which gives the movement ⁸⁵ considerable rapidity; they consist, on the other hand, of a lifting member which acts upon the movable tooth to rock it, so that it only projects from the drum 70 at a fixed point, and which holds it in a rigid manner ⁹⁰ in this new position.

On the shaft 62⁴ of the disc 62 is keyed a finger 63', the edges of which are chamfered and it is arranged radially so as to act between the passage of the disc from ⁹⁵ 0 to 9. Below this finger there is arranged, in a suitable frame 121 fixed to the base 5 of the machine, a rod 122 which can move vertically therein and terminates at its upper end in a head 123 of conical or other ¹⁰⁰ suitable shape: this rod carries at its lower end a finger 124 fixed thereon in any suitable manner.

The flange 68' of the member 68 is held by its periphery between the lateral faces of a notch 125 formed in the extremity of the arm 126 of a lever 127 pivoted at 128 on a cheek integral with the frame 121. The lever 127 terminates at its free end in a finger 132 having two abutments 133 and 134 ¹⁰⁵ 110

connected by a cam-surface 135 having a steep incline, these two abutments being intended to hold the lever 127 in its two extreme positions by means of a roller 131 carried by an arm 130 pivoted to a rigid arm 130' fixed to the frame 121; a return-spring 129 assures constant contact of the roller 131 on the lever 127.

The part 68 carries a sleeve 136 terminating in a connecting member 137 and which can slide longitudinally on the shaft 69 of the drum 70. This plate carries, fixed thereon, a rod 68⁴ arranged parallel to the shaft 69 and having a block 68⁹ for actuating the movable tooth 72. The active portion of this latter is preferably of slight length as can be seen in Fig. 1, and can only project on the cylinder 70 at the exact spot at which it is to act. The movable tooth 72 is prolonged in a recess in the drum 70 to which it is pivoted at 72' near its rear end and it has two shoulders 72² and 72³ both of which normally rest upon the actuating block 68⁹ either upon its upper face or upon its lower face according to the position occupied by the movable tooth 72. It is to be observed that this arrangement differs entirely from that described in French Patent 522856, which comprised a bell-crank lever, the oscillation of which controlled the radial movement of the movable tooth by the action of pins; the application of the shoulders acting after the manner of steep cams upon the arms of multiplying levers so as to enable absolute instantaneity of movement to be obtained.

This mechanism operates in the following manner:

When the disc 62 of any order, having been brought into such position that the "9" appears at the opening provided for this purpose in the cover of the machine, is again moved through an angle corresponding to one unit, that is to say, through a tenth of a revolution, the finger 63', which is fixed to its shaft 62⁴, engages, by means of its bevelled edge, the conical head 123 of the rod 122 and depresses this latter, as can be seen from Fig. 1. The finger 124 of this rod is depressed in consequence and as it bears constantly upon a point formed on the lever 127, this latter oscillates about its axis 128 and pushes the roller 131 away, causing it to rise on the surface of the cam 135, the spring 129 giving way so as to permit of this movement. As the surface 135 is very steeply inclined, that is to say, that its extremity located near the abutment 133 is further remote from the axis of oscillation 128 than the extremity adjacent the abutment 134, the roller 131 runs over this surface very rapidly under the action of the spring 129, and consequently depresses the lever 127, causing it to oscillate at a high speed about its pivot 128. The member 68 is therefore

drawn sharply to the right and, owing to the accelerator constituted by the cam 135 and the spring 129, this takes place so suddenly that its movement is effected immediately the rod 122 has begun to be depressed by the finger 63'.

When the rod 68⁴ thus drawn by the action of the arm 126 slides in the cylinder 70, the shoulder 72³ of the tooth 72 is raised by the abutment 68¹⁰ of the block 68⁹ and rises upon the upper face of this latter, while its shoulder 72² falls along the abutment 68¹¹ on its lower face. The result is that the tooth 72 rocks about its axis 72' and is caused to project on the outside of the cylinder 70. It should be noticed that the shoulder 72³ is raised by the abutment 68¹⁰ as soon as the block 68⁹ begins to move towards the right so that the tooth 72 is in its exterior position starting from this moment, that is to say, in the required position to engage the corresponding calculating wheel 76², which transmits the required angular displacement of one tenth of a revolution to the disc 62 of the immediately higher order. The continuation of the movement of the block 68⁹ only has therefore the effect of fixing the tooth 72 in its working position owing to the locking of the shoulder 72³ on the upper face of the block. This position is shown in Fig. 1. The return of the parts to their normal position is effected by the device provided for this purpose in French Patent No. 522856, which consists of an abutment 68³, acting on a cam 68².

It will be seen that the arrangement just described enables the movable tooth 72 to be put into action instantaneously, thanks to the acceleration obtained successively, on the one hand, by the steep incline of the cam-surface 135 and by the action of the spring 129 and on the other hand, by the relative positions of the shoulders 72² and 72³ and of the abutments 68¹¹ and 68¹⁰.

We claim:

1. In a tens-carrying mechanism for computing machines, the combination of a stepped drum, a movable tooth on said drum, means for causing said tooth to project from the drum on the passage of tens and auxiliary means for accelerating the motion of the movable tooth.

2. In a tens-carrying mechanism for computing machines, the combination of a stepped drum, a movable tooth on said drum, means for causing said tooth to project from the drum on the passage of tens and a spring adapted to accelerate the motion of the movable tooth.

3. In a tens-carrying mechanism for computing machines, the combination of a stepped drum, a movable tooth on said drum, means for causing said tooth to project from the drum on the passage of tens, auxiliary means for accelerating the motion

of said tooth into its projecting position and means for locking said tooth in its projecting or retracted position.

mounted in said drum, said block having
cam surfaces adapted to engage said tooth
and means actuated on the passage of tens to
slide said block to rock said tooth. 65

4. In a tens-carrying mechanism for computing machines, the combination of a stepped drum, a movable tooth pivoted to said drum, and means actuated on the passage of tens to rock said tooth to cause it to project beyond the periphery of said drum.

12. In a tens-carrying mechanism for computing machines, the combination of a stepped drum, a movable tooth pivoted to said drum, a block for rocking said tooth to cause it to project from said drum slidably mounted in the latter, cam-surfaces on said block adapted to rock said tooth on passage of tens and to lock it in position and spring actuated means released on passage of tens to slide said actuating block.

10 5. In a tens-carrying mechanism for computing machines, the combination of a stepped drum, a movable tooth pivoted to said drum, means actuated on the passage of tens to rock said tooth to cause it to project

13. In a tens-carrying mechanism for computing machines, the combination of a stepped drum, a movable tooth pivoted to said drum, a block for rocking said tooth to cause it to project into operative position slidably mounted in said drum, a spring tensioned rocking-lever engaging said block and means actuated on passage of tens to release said rocking lever to slide said block.

15 beyond the periphery of said drum and means for locking said tooth in position.

14. In a tens-carrying mechanism for computing machines, the combination of a stepped drum, a movable tooth pivoted to said drum, a block for rocking said tooth to cause it to project into operative position slidably mounted in said drum, a rocking lever engaging said block at one end and terminating at the other end in a steep cam surface having an abutment at each end, a spring tensioned lever engaging one of said abutments to hold said rocking lever in the position in which said movable tooth is in operative position and means operated on passage of tens to release said spring tensioned lever to allow it to pass along said cam-surface to the other abutment thereby rocking said rocking lever.

6. In a tens-carrying mechanism for computing machines, the combination of a stepped drum, a movable tooth pivoted to said drum, means actuated on the passage of tens to cause said tooth to project beyond the periphery of said drum and a spring adapted to accelerate the motion of said tooth.

14. In a tens-carrying mechanism for computing machines, the combination of a stepped drum, a movable tooth pivoted to said drum, a block for rocking said tooth to cause it to project into operative position slidably mounted in said drum, a rocking lever engaging said block at one end and terminating at the other end in a steep cam surface having an abutment at each end, a spring tensioned lever engaging one of said abutments to hold said rocking lever in the position in which said movable tooth is in operative position and means operated on passage of tens to release said spring tensioned lever to allow it to pass along said cam-surface to the other abutment thereby rocking said rocking lever.

7. In a tens-carrying mechanism for computing machines, the combination of a stepped drum, a movable tooth pivoted to said drum, means tending to rock said tooth to cause it to project beyond the periphery of said drum, means for normally locking said rocking means in the inoperative position and means actuated on the passage of tens for releasing said rocking means.

15. In a tens-carrying mechanism for computing machines, the combination of a stepped drum, a movable tooth pivoted to said drum, a block for rocking said tooth to cause it to project into operative position slidably mounted in said drum, a rocking lever engaging said block at one end and terminating at the other end in a steep cam surface having an abutment at each end, a spring-tensioned lever engaging one of said abutments to hold said rocking lever in the position in which said movable tooth is inoperative, and a rod engaging said rocking lever and adapted on passage of tens to move said rocking lever to release said spring tensioned lever to allow the latter to act on said cam-surface to rock said rocking lever for the purpose set forth.

35 8. In a tens-carrying mechanism for computing machines, the combination of a stepped drum, a movable tooth pivoted to said drum, means tending to rock said tooth to cause it to project beyond the periphery of said drum, means for normally locking said rocking means in the inoperative position and a cam adapted, on the passage of tens, to release said rocking means.

15. In a tens-carrying mechanism for computing machines, the combination of a stepped drum, a movable tooth pivoted to said drum, a block for rocking said tooth to cause it to project into operative position slidably mounted in said drum, a rocking lever engaging said block at one end and terminating at the other end in a steep cam surface having an abutment at each end, a spring-tensioned lever engaging one of said abutments to hold said rocking lever in the position in which said movable tooth is inoperative, and a rod engaging said rocking lever and adapted on passage of tens to move said rocking lever to release said spring tensioned lever to allow the latter to act on said cam-surface to rock said rocking lever for the purpose set forth.

9. In a tens-carrying mechanism for computing machines, the combination of a stepped drum, a movable tooth pivoted to said drum, means tending to rock said tooth to cause it to project beyond the periphery of said drum, means for normally locking said rocking means in the inoperative position, a rod engaging said locking means, and 45 50 a cam adapted, on passage of tens, to actuate said rod to release said rocking means.

In witness hereof, we have hereunto set
our hands this 5 day of January 1922.

10. In a tens-carrying mechanism for computing machines the combination of a stepped drum, a movable tooth pivoted to said drum, means actuated on passage of tens to rock said tooth to cause it to project beyond the periphery of said drum, and cam-surfaces on said rocking means for locking said tooth in position.

- our hands this 5 day of January 1922.

60 11. In a tens-carrying mechanism for computing machines, the combination of a stepped drum, a movable tooth pivoted to said drum, an actuating block slidably
